UNITED STATES PATENT OFFICE.

ARTHUR H. PLEASANTS, OF BALTIMORE, MARYLAND.

DESIGN FOR AN INDICATOR-HAND FOR COMPUTERS, GUIDE MAPS, CHARTS, AND
SIMILAR DEVICES.

50,847.

Specification for Design.

Patented May 29, 1917.

Application filed December 1, 1916. Serial No. 134,524. Term of patent 3½ years.

To all whom it may concern:

Be it known that I, ARTHUR H. PLEASANTS, a citizen of the United States, residing at Baltimore, in the State of Maryland, have invented a new, original, and ornamental Design for Indicator-Hands for Computers, Guide Maps, Charts, and Similar Devices, of which the following is a specification, reference being had to the accompanying drawing, forming part thereof.

The figure is a plan view of an indicator hand, showing my design.

I claim:—

The ornamental design for an indicator hand for computers, guide maps, charts, and similar devices, as shown.

ARTHUR H. PLEASANTS.
